United States Patent Office

Des. 207,569
Patented May 2, 1967

207,569

PIPE

Kikuo Hayashi, 2119½ Hoagland Ave.,
Fort Wayne, Ind. 46804

Filed Aug. 4, 1966, Ser. No. 3,345

Term of patent 14 years

(Cl. D85—8)

Fig. 1

Fig. 2

Fig. 3

Fig. 4

Fig. 5.

FIG. 1 is a side elevational view of a pipe showing my new design;

FIG. 2 is a top plan view thereof;

FIG. 3 is a stem end view thereof;

FIG. 4 is a bowl end view thereof; and

FIG. 5 is a reduced scale perspective view thereof.

The essential features of the design are shown in full lines.

I claim:

The ornamental design for a pipe, as shown and described.
